UNITED STATES PATENT OFFICE.

JOHN B. HODGES, OF HULETT, WYOMING.

ROAD-GRADEER.

1,331,812.

Specification of Letters Patent. Patented Feb. 24, 1920.

Application filed September 3, 1919. Serial No. 321,370.

To all whom it may concern:

Be it known that I, JOHN B. HODGES, a citizen of the United States, and a resident of Hulett, in the county of Crook and State 5 of Wyoming, have invented a certain new and useful Improvement in Road-Graders.

My present invention relates generally to road machines and particularly to road making devices of such nature as adapts the 10 same for use as graders, levelers, snow scrapers and the like, my object being the provision of a simple, inexpensive and durable arrangement, capable of ready, quick and convenient adjustment and of effective use.

15 In the accompanying drawing, illustrating my present invention, and forming a part of this specification,

Figure 1 is a top plan view,

Fig. 2 is a transverse sectional view showing a slight rearrangement of the parts, and

Fig. 3 is a detail vertical section taken on line 3—3 of Fig. 2.

Fig. 4 is a side view, partly in elevation and partly in section, illustrating a slightly 25 modified form.

Referring now to these figures, my invention proposes an apparatus including a pair of side members 10 and 11 each in the form of an angle bar one flange of which 30 is disposed vertically and one horizontally, the latter turned either in an inward direction, as seen in Fig. 1 or an outward direction as in Fig. 2 depending upon the desires of the user and the particular use 35 to which it is put.

The horizontal flange of each side bar has openings 12 intermediate its ends and openings 13 at the forward ends thereof, the former receiving bolts for adjustably securing 40 a transverse seat board 14. The front openings 13 receive clevises or other draft attaching means (not shown). At their rear ends, the side bars having laterally projecting staples 15 over which are extended 45 the end of a flexible wire loop 16. Taper pins 16^a are thrust downwardly through the staples to secure the connecting loop, thus permitting it to function as a connection and still allow the forward ends of the side bars 50 to be adjusted toward and away from one another.

Adjacent to its forward end the apparatus has an adjustable spacing arrangement including adjusting arms 17 and 18, 55 each bolted by a bolt 18^a at its outer end through one of the side bar openings 13,

The inner ends of these arms 17 and 18 overlap, and the inner end of arm 17 has a longitudinal series of teeth 19, into the notches between which a single projecting hook 20 at the inner end of the arm 18 extends. A clamp 21 surrounds the lapped ends of arms 17 and 18 and consists of a lower plate 22 as in Fig. 3 to one end of which is hinged one end of a U-shaped piece 61 23, the opposite end of which may be joined to the opposite end of the plate by a clamping bolt 24. This arrangement makes for quick effective adjustment and joins with the remaining features in providing for 70 ready interchange to fit the various uses to which it is to be put.

I claim:

1. A device of the character described, comprising a pair of side angle bars having 75 their upper horizontal flanges provided with apertures adjacent to one end, having their upright ends provided with laterally projecting staples adjacent to their opposite ends, a flexible loop extending around the 80 last mentioned ends of the angle bars and over the staples, taper pins projecting through the staples securing the loop end in position and an adjustable connection between the outer ends of the bars mounted 85 through the said apertures.

2. A device of the character described, including a pair of side angle bars, means flexibly securing the bars in engagement with one another at one end and an adjustable 90 connection for the opposite end, including a pair of connecting arms secured at their outer ends by the angle bars, one of said arms having a series of notches extending therealong and the other bar having a tooth 95 at its inner end for adjustable engagement with the said notches and a clamp for securing the inner ends of the arms in engaged relation.

3. A device of the character described including a pair of side angle bars having apertures adjacent to one end, a flexible connection uniting said bars at their opposite end and an adjustable connection for the first mentioned end including a pair of connecting arms bolted at their outer ends through the side bar openings, said arms having relatively engaging means at their inner ends and a clamp for securing the same in engaged relation.

JOHN B. HODGES,
